CIRCUIT BREAKER

Frederick B. Johnson, Murrysville, Pa., assignor
to Westinghouse Electric & Manufacturing
Company, a corporation of Pennsylvania

Original application January 24, 1931, Serial No.
510,981. Patent No. 2,037,418, April 14, 1936.
Divided and this application March 17, 1936,
Serial No. 69,325

6 Claims. (Cl. 200—147)

My invention relates to circuit breakers and more particularly to an arc-extinguishing structure therefor having the capability of opening high-voltage, large-current arcs in air or gas.

5 The circuit breaker of my invention is of the type in which an arc is drawn and moved into a converging slot in a plurality of spaced conducting plates and split up into a plurality of short arcs. The short arcs are rotated at a high velocity between the conducting plates by reason 10 of the force exerted upon them by a radial field set up by coils between spaced groups of the plates.

15 My invention is a further development of circuit breakers of the type shown in the copending application of R. C. Dickinson, Serial No. 511,010, filed Jan. 24, 1931, now Patent No. 1,927,888, issued September 26, 1930, and assigned to the assignee of this application.

20 This application is a division of my copending application Serial No. 510,981, filed January 24, 1931, and issued April 14, 1936 as Patent No. 2,037,418.

An object of my invention is to provide an arc 25 extinguisher in which the conducting plates between which the arc is rotated by the radial magnetic field have an opening therethrough within the radial field and in which the arc may play as a long arc before it is split up between the plates, with means for preventing the short arcs 30 from restriking as a long arc through the openings as it is rotated past the opening by the radial field.

This and other objects and advantages of my 35 invention will be made apparent and more fully understood from the following description of the specific embodiment of my invention illustrated in the drawings, in which

Figure 1 is a diagrammatic view, partially in 40 section, of my circuit interrupter.

Fig. 2 is a sectional view, through the circuit interrupter, taken through the deionizing plates on the line II—II of Fig. 3.

Fig. 3 is a sectional view through the deionizing plates, taken on the line III—III of Fig. 2.

Figs. 4, 5, 6, and 7 are side elevational views of the metal plates which are assembled to form the deionizing structure, and

Figs. 8 and 9 are elevational views of the sheets 50 of insulating material which are employed to space apart the metal plates.

Referring to Fig. 1, my circuit interrupter 11 comprises main contacts 13 and 15, which complete a circuit between conductors 17 and 19, and 55 a pair of arcing contacts 21 and 23 which are

connected in parallel with the main contacts 13 and 15. Main contacts 13 and 15 and arcing contacts 21 and 23 are actuated by any suitable operating mechanism so that the main contacts 13 and 15 are opened first, with practically no 5 arc, and the arcing contacts 21 and 23 are opened later, drawing an arc which is transferred to a pair of stationary arc horns 25 and 27 by means of the moving arc horn 29 which is attached to the moving arcing contact 23. Stationary arc 10 horns 25 and 27 and the moving arc horn 29 are each made of magnetic material, such as iron, to cause a more rapid transfer of the arc due to the attraction thereof to the iron members caused by the local fields set up in the iron by the arc 15 current.

The arcing horns 25 and 27 have arc-terminal portions 31 and 33 and current-conducting portions 35 and 37. The arc horns are each connected in parallel with the main contacts 13 and 15 through conductors 39 and 41 which are connected to the outer ends of the current-carrying portions 35 and 37. This causes the current to flow in such direction in each of the arc horns that the magnetic reaction between the fields, 25 due to the current in the arc horns and due to the current in the arc, is such as to cause the arc to be moved upwardly on the horns into the deionizing structure.

The deionizing structure comprises a plurality 30 of groups 43 of main deionizing plates having coil sections 45 therebetween. The deionizing plates and coils are assembled between end plates 47 and 49 which are electrically connected to the upper ends of the arc horns 25 and 27. The 35 plates are secured together by means of a through bolt 51 in an insulating tube 53 of a fibrous material impregnated with a condensation resin extending through the deionizing structure. The lower portion of the structure is secured together 40 by a pair of tie rods 55 which may be of wood impregnated with a condensation resin having end pieces 57 and which support the lower outer edges of the deionizing plates, as shown in Fig. 2.

As shown in Figs. 2 and 3, each of the groups 43 of deionizing plates comprises a plurality of copper plates 59, each of which is surrounded by an iron plate 61, which is placed in the same plane in edge-to-edge relation with the plate 59, 50 as shown in Figs. 2 and 7. By having the copper plates 59 in edge-to-edge relation with the iron plates 61, heat may be conducted from each of the copper plates to one of the iron plates, thus adding the heat capacity of one of the iron plates 55

to the heat capacity of each of the copper plates and making it possible to use smaller copper plates than would otherwise be possible for a structure of the same interrupting ability. Each 5 of the conducting plates 59 has a narrow extension 63 extending from the lower end thereof and provided with a narrow converging slot 65. The slot 65 is symmetrical with the main portion of the plate 59 and has a converging tip 67 which 10 curves away from the axis of the plate. Each of the magnetic plates 61 has a wide portion 69 surrounding the body portion of the plates 59 and a narrow portion 71 beside the extensions 63 of the copper plates 59.

15 In order to prevent warping or buckling of the narrow extension 63, such as would close the slot 65 when subjected to the heat of the arc, each of the copper plates has a projection 73 which extends into a cutout portion 76 in each of the 20 iron plates 61. This interlocks the lower ends of the two plates and prevents movement of the narrow extensions 63 out of proper alignment. Each of the copper plates 59 is provided with a slot 75 extending from the center thereof to the outer 25 edge to prevent the flow of eddy currents, thereby reducing the magnetic losses.

The composite plates formed by the iron plates 61 and copper plates 59 are assembled in groups, the individual plates of which are spaced apart 30 by the insulating members 77 and 79 shown in Figs. 2 and 9 and insulating washers 81 around the opening 64 in the center of each of the copper plates 59. Copper plates 59 are so assembled that all of the plates in each group have the 35 curved portion 67 of the converging slot curved to the same side of the axis of the plates. The slots 75 are positioned on opposite sides of adjacent plates throughout each group, thus eliminating the continuous opening through the stack 40 in which the arc could play, which would result if the slots 75 were on the same side of all of the plates.

The insulating sheets 77 and 79 may be of fish paper and so shaped as to provide an annular 45 path 83 in which the arc is rotated. The insulating spacers 77 and 79 have depending portions 85 and 89 which define a narrow arc path 91 along the slot 65, and a curved portion 93 which leads the arc into the annular path 83 along a 50 tangent thereto. Insulating spacers 77 have projections 84 which extend over the tips of the slots 67 and prevent the arc from striking back through the slots on each revolution of the arc, as it rotates across the tops of the slots. As 55 shown in Fig. 2, the insulating spacers 77 and 79 are made of such width that they over-lap the joint between the conducting plates 59 and the magnetic plates 61 adjacent to the path over which the arc is moved. This prevents the possibility of the arc playing in the joints between the plates. Each insulating sheet 79 has a projection 97 defining the upper portion of the annular path and leaving a ventilating opening 99 leading from one side thereof.

Above the extension 97, is provided a rapidly diverging ventilating passage 101 in which the arc 60 gases may expand and come into contact with large surfaces of both the iron and copper plates, whereby the gas is rapidly cooled and ions are removed therefrom.

The arc horns 25 and 27 are formed of spaced sheets of iron having ventilating passages 103 therebetween. The ventilating passages 103 permit the flow of gas out of the end of the stack 75 ahead of the arc as it is moved upwardly on the

arc horns and also permit upward ventilation through the stack after the arc has been moved into the spaces between the deionizing plates. It is thus seen that a continuous ventilating passage is provided from the lower end of the 10 arc chamber through the whole deionizing stack. This allows a through flow of gas to rapidly cool the arc and the plates 59 and 61 so that the heat of the arc is rapidly dissipated, which allows the circuit interrupter to be used 15 for interrupting heavy currents with a duty cycle, which calls for a large number of successive interruptions of the circuit.

The insulating plates 77 and 79 are assembled 15 in such relation to the copper plates 59 that the curved tips 67 of the slots 65 are aligned, and the direction of rotation of the arc around the annular path 83 is such that the motion of the arc adjacent to the ventilating opening 99 is in the opposite direction to the flow of gases out of the 20 passage. This prevents the arc from being blown out of the annular path into the ventilating passage by reason of the flow of gas through the stack.

The arc is rotated around the annular path 83 25 by the action of a radial magnetic field set up by radial field coils 105 which are spaced between adjacent groups 43 of deionizing plates.

As shown in Fig. 1, the directions of the fields, 30 as indicated by the arrows 107, are opposite in alternate groups 43 of deionizing plates. The arc is, therefore, rotated in opposite directions in alternate groups of deionizing plates. The positioning of the conducting plates 59 and the insulating spacers 77 and 79 is, therefore, reversed 35 in alternate groups, as is indicated by the broken lines in Fig. 2.

Each of the magnetizing-coil sections 45 comprises a radial field coil 105 which is placed between a pair of coil-end plates 109, as shown in 40 Fig. 5. Each end of each coil 105 is electrically connected to one of the coil-end plates 109. At the lower end of each coil-end plate 109 is positioned a coil-end transfer plate 111 which is spaced from the coil-end plate 109 by a gap 113. 45 Each coil-end transfer plate 111 has a converging slot 115 therein which extends to a point slightly below the gap 113. Each plate 109 has a hole 117 through which the bolt for securing the plates together is passed, and a slot 119 for reducing 50 eddy currents.

A number of transfer plates 121 are positioned 55 between the coil-end transfer plates 111 below each of the radial field coils 105. Each of the transfer plates 121 has a converging slot 123 similar to the slots 115 in coil-end transfer plates 111. The transfer plates are spaced apart by insulating spacers 125 of fish paper which have a narrow portion 127 to form a path in which the arc is moved and an enlarged circular portion 129 60 at the upper end of the passage 127.

At each end of the stack of plates and radial field coils is an end plate 131 which is electrically connected in the circuit to be interrupted. Plate 131 has an opening 133 for the through bolt 51, 65 and a converging slot 135 similar to the slots 123 and 115, as shown in Fig. 4.

As shown in Fig. 2, slots 115, which are aligned 70 with slots 123 and 135, are shorter and inwardly tapered at a more rapid rate than slots 65 in plates 59. As the arc is moved up into the aligned slots in all of the plates, the arc is first constricted in the tips of the slots 115, 123 and 135 while still in a relatively wide portion of the slots 65. The arc is then transferred to the coil-end transfer 75

plates 111 and transfer plates 121, splitting the arc into a plurality of short arcs between transfer plates 121 and a plurality of arc sections between plates 111. Each of the arc sections may be freely moved into the stack because of the width of the slots 65. As the plurality of sections of the arc are moved upwardly, they cross the gap 113 between the coil-end plates 109 and coil-end transfer plates 111. The voltage drop through the radial coils 105, connected between the plates 109, is smaller than that necessary to maintain the series of arcs between the transfer plates 121 so that the arcs therebetween are extinguished, and the current flows through the radial field coils 105. Since the arc is moving in relatively wide portions of the slots 65 at the time that it crosses the gap 113, there is not much resistance to its movement so that it crosses the gap 113 without serious burning of the coil-end plates 109.

As the arc is moved farther, the slot 65 gradually converges so that each of the arc sections is concentrated into an arc of high current density and small cross section. The arc is then above the narrow extensions 71 on the magnetizing plates 61 so that it is no longer acted upon by the blow-in field but is within the much stronger field set up by the radial coils 105 which provide a field of such strength that the arc may be rapidly moved along the tips 67 of the slots 65 and split between the plates 61. This use of the radial field for splitting each section of the arc into a plurality of short arcs is advantageous in that it is not necessary to provide a blow-in field of such strength as to provide the force necessary to split the arc into a plurality of short arcs. The arc then enters tangentially into the annular path 83 and is rapidly rotated until the occurrence of the zero point on the alternating-current wave when it is extinguished.

As shown in Figs. 1 and 2, a plurality of iron laminations 137 are provided to form extensions of the iron plates 61 beside the arc-drawing contacts and arc horns. The iron laminations 137 are spaced apart by sheets of fish paper 139, shaped similar to the iron plates 137. The lengths of the laminations 137 are varied in different sections of the deionizing structure. The end sections 141 are made of such length as to extend to the arc horns 25 and 27. The section 143 adjacent to the arcing contacts 21 and 23 and main contacts 13 and 15 are made longer than the other sections so as to extend to a point adjacent to the contacts to blow the arc into the deionizing structure. The intermediate section 145 is of a length between those of the other sections so as to extend beside the moving arc horn 29. The provision of iron laminations 137 provides an iron path for the flux set up by the arc current as soon as the arc is drawn, in order to move the arc into the deionizing structure in cooperation with the flux set up by the current flowing in the arc-terminal portions 31 and 33 of arc horns 25 and 27. The edges of laminated members 137 are protected from the arc by fibre plates 147 having arc-resisting inserts 149 of asbestos or other suitable material. An insulating sheet of fish paper 150 is placed in the joint between the lower edges of the deionizing plates and the iron laminations 137 and also extends between the laminations 137 and fibre plates 147. The iron laminations 137 and fish paper spacers are secured in the structure by being clamped between wood blocks 151 and the fibre plate 147.

A static shield is provided in the form of a

pair of sheets 153 of insulating material, such as a fibrous material impregnated with a condensation resin and having sheets of tinfoil 155 embedded therein.

From the above description it is seen that my invention provides an air circuit breaker which is capable of interrupting large currents at high voltages in a most effective manner.

While I have described a specific embodiment of the invention, it should be understood that the various novel features thereof may be used in various combinations, and I am not to be limited by the specific description except as indicated by the scope of the following claims.

I claim as my invention:

1. In an arc extinguisher, a plurality of spaced plates each providing a path about which the arc may be rotated, an opening through said plates in which the arc may play, means for moving the arc from said opening into said path, and means for guiding the arc past said opening as it rotates and preventing it from moving into the opening.

2. In an arc extinguisher, a plurality of spaced plates of conducting material each providing an annular path for the arc, an opening through a plurality of said plates in which the arc may play as a long arc, means for moving the arc from said opening into the plates, thereby splitting it into a plurality of short arcs, and rotating the short arcs about the annular paths, and means of insulating material for guiding the short arcs past the opening through the plates as they rotate and preventing the arcs from restriking through the opening as a single long arc.

3. In an arc extinguisher, a plurality of spaced plates of conducting material each providing an annular path for the arc about which the arc may be rotated more than a whole revolution, a coil for setting up a radial magnetic field across said annular arc paths, an opening through a plurality of said plates of conducting material, said opening having a portion within said radial magnetic field, means for causing an arc to play in said opening, and means of insulating material for guiding the short arcs past the opening through the plates as they rotate and preventing the arcs from restriking through the opening as a single long arc.

4. In an arc extinguisher, a plurality of members of conducting material between which the arc may be split up into shorter arcs, said conducting members each providing a recurrent path about which the short arcs may be rotated, a coil for causing a magnetic field for rotating the arcs, an opening through a plurality of said members of conducting material, means for causing an arc to play in said opening, said opening having a portion within the magnetic field for rotating the arc, and insulating means around said opening on the side thereof which is approached by the arc as it rotates to prevent the arc from moving into the opening as it rotates around the recurrent path.

5. In an arc extinguisher, a plurality of spaced plates of conducting material each providing an annular path for the arc about which the arc may be rotated more than a whole revolution, a coil for setting up a radial magnetic field across said annular arc paths, an opening through a plurality of said plates of conducting material, said opening having a portion within said radial magnetic field, means for causing an arc to play in said opening, and said coil being energized while the arc plays in said opening in a plurality

of said plates whereby the radial magnetic field set up by the coil moves the arc from the opening into the plates and splits it up into shorter arcs and then rotates the shorter arcs around said annular paths on the conducting plates, and means of insulating material for guiding the short arcs past the opening through the plates as they rotate and preventing the arcs from restriking through the opening as a single long arc.

5 10. 6. In an arc extinguisher, a plurality of members of conducting material between which the arc may be split up into shorter arcs, said conducting members each providing a recurrent path about which the short arcs may be rotated, a coil for causing a magnetic field for rotating the arcs, an opening through a plurality of said

members of conducting material, means for causing an arc to play in said opening, said opening having a portion within the magnetic field for rotating the arc, said coil being energized while the arc plays in said opening through a plurality of said members of conducting material whereby said magnetic field caused by the coil for rotating the arc is effective for moving the arc from said opening and causing it to be split up into shorter arcs between said members of 10 conducting material, and insulating means around said opening on the side thereof which is approached by the arc as it rotates to prevent the arc from moving into the opening as it rotates around the recurrent path.
